UNITED STATES PATENT OFFICE

WILLIAM STONE LUCKETT, OF NEW YORK, N. Y.

CIGARETTE PACKAGE

Application filed January 19, 1929. Serial No. 333,579.

My invention relates to boxes or containers for cigarettes, and one object of my invention is to provide a dispensing container substantially rectangular in shape and designed to hold cigarettes in perfect condition; such container having an opening in one of its narrow walls through which the cigarettes may be dispensed.

A further object of my invention is to provide a container having a support onto which the cigarettes may be delivered; such support constituting a cover or closure for the open end of the box or container and including a tab or tongue to be inserted through a slot formed in a wall of the box or container and serve as the retaining means for the cover or closure.

And a further object of my invention is to provide a special pocket or chamber within the container into which such tongue may be slipped to avoid contact with and possible damage to the articles contained therein, such as cigarettes.

These and other features of my invention are more fully described hereinafter, reference being had to the accompanying drawings, in which:

Figure 1 is a perspective view of a box or container within the scope of my invention, partly broken away to illustrate its construction.

Fig. 2 is a plan view of a blank from which a container within the scope of my invention may be made.

Figs. 3 and 4 are views similar to Fig. 2, illustrating other forms of blanks from which containers within the scope of my invention may be made.

Fig. 5 is a cross sectional view of a filled and sealed container made from a blank such as shown in Fig. 2 or Fig. 4.

Fig. 6 is a cross sectional view of a filled and sealed container made from a blank such as shown in Fig. 3, and

Fig. 7 is a sectional view illustrating a container in the dispensing position.

My present container is in the form of a rectangular box or carton preferably made of very stiff cardboard in order to serve as a practical holder for cigarettes and maintain

its shape until all of the contents have been used. It comprises a shell or body having front and back walls 1 and 2, end walls 3 and 4, respectively, top and bottom walls 5 and 6, respectively, and a closure flap 7.

The closing flap or cover includes a tongue portion, and such tongue portion will have a tendency to remain in a position at an angle to the closure flap, substantially as illustrated by dotted lines in Fig. 5, when opened. When the opened box is inverted to the position illustrated in Fig. 7, which is the position in which the box is placed when it is desired to deliver the cigarettes therefrom, the cigarettes will roll out singly and be supported by the closure flap or cover, as clearly illustrated in said view.

In order to take care of the tongue and provide for its insertion in a position whereby it will be retained in place, retention in such position being initially helped by the presence of the usual revenue stamp at A, required upon containers for tobacco products; such stamp, indicated at A, also acting as a seal, I provide a supplemental pocket or chamber 8 within the box into which such tongue is passed and is thereby maintained out of contact with the cigarettes. With such construction there is no danger of injuring the cigarettes upon successive insertions of the tongue to hold the box closed. In order that the tongue may enter this chamber, the top wall 6, which constitutes the upper wall of the same is slotted at 9, and such slot should have such a width dimension that its walls will exert sufficient frictional contact with the tongue as to retain it in place during the use of the package, and as long as such use is necessary to effect consumption of the contained cigarettes.

The chamber receiving the tongue is provided by an extension carried by the top wall, such extension being folded in the manner indicated. It may be connected to the front wall by gluing a portion thereto, or it may extend to the bottom of the box and underlie the cigarettes. The portion between the slotted top wall and the portion contacting with the front wall provides an inclined surface with-

in the main chamber or space of the container over which the cigarettes may roll when they are delivered therefrom, as indicated in Fig. 7.

- 5 My improved box may be of a single section blank substantially like that illustrated in Fig. 2, wherein the dotted lines indicate the bends or folds. In this blank the end wall 3 is shown as provided with an extension 3^a which may be attached to the front wall 1 by suitable adhesive. In lieu of this arrangement, the front wall section 1 may have an extension 1^a, indicated by broken lines, Fig. 2, which will overlie (inside or outside the container as may be desired) said end wall 3. The end walls 3 and 4 may also be provided with extensions or tabs 3^a and 4^a which will overlie the bottom wall 5 (inside or outside the container as may be desired). 10 The bottom wall 5 may be provided with an extension 5^a which will be bent into upstanding position for engagement with the front wall 1. The top wall may be continuous with the front wall and comprises sections 6, 6^a and 6^b which are bent to form the supplemental space or chamber 8 arranged within the main chamber receiving the cigarettes; the portion 6 forming the top wall proper and being provided with the narrow slot 9 for the reception 15 of a tongue carried by the closure 7. This wall 6 is substantially parallel with the bottom wall 5. The portion 6^a is disposed in an inclined position with respect to the top wall and the front wall, as clearly shown in the sectional views, Figs. 5 and 7, and the portion 6^b is brought into engagement with the inner face of the front wall and may be secured thereto by gluing or otherwise, as may be desirable or advantageous in the process of manufacture. 20 The flap or closure 7 forms an extension of the rear wall 2 and has a tongue preferably bent on parallel lines to define the portions 7^a and 7^b which are inserted in the slot 9; such closure flap partly overlying the top wall 6 and in such relation thereto that the tongue portions 7^a and 7^b may enter said slot. This slot is very narrow so that its walls are in frictional engagement with the tongue, and serve to hold the flap in closed 25 position; the portions 7^a and 7^b occupying substantially the position illustrated in Fig. 5.
- It will be understood that the shape of the blank is not material as long as a structure such as illustrated in Figure 1 of the drawings is produced, and in Figs. 3 and 4 I have shown modified forms of blanks.
- The blank shown in Fig. 3 is substantially like that shown in Fig. 2, except that the portion 6^b is extended as indicated at 6^{bb} so as to provide portions to lie within the box against the front and bottom walls and underneath the cigarettes, as clearly indicated in the sectional view, Fig. 6.
- 30 In the use of a blank such as illustrated in

Fig. 4, the end walls 3 and 4 may be provided with extensions 3^b and 4^b which may be attached by suitable adhesive to the front wall 1; inside or outside as the case may be. The bottom wall 5 may lie between the front and rear walls 1 and 2, and may be provided with the extensions 5^a which will be bent into upstanding position for engagement with the lower part of the end walls 3 and 4. 35 In lieu of this arrangement, said end walls 3 and 4 may be provided with extensions 3^a and 4^a, indicated by broken lines, to overlie the bottom wall 5 (inside or outside the container) as in the form of blanks illustrated in Figs. 2 and 3. The top wall is continuous with the front wall and comprises the sections 6, 6^a and 6^b which are bent to form the supplemental space or chamber 8 within the main chamber receiving the cigarettes, as in the use of the blanks shown 40 in Figs. 2 and 3. The portion 6 forms the top wall proper and is provided with the narrow slot 9, and this wall 6 is substantially parallel with the bottom wall 5. The portion 6^a is disposed in an inclined position with respect to the top wall and the front wall, as clearly shown in the sectional view, Fig. 4, and the portion 6^a is brought into engagement with the inner face of the front wall and secured thereto by gluing or otherwise as may be desirable or advantageous in the process of manufacture. The flap or closure 7 forms an extension of the rear wall 2 and is provided with the tongue bent on parallel lines to define the portions 7^a and 7^b which are inserted in the slot 9, as 45 in the other forms illustrated.

When it is desired to dispense the cigarettes, the closure flap is released and the container inverted and disposed in the position illustrated in Fig. 7. The cigarettes will then roll out and be supported by the tongue; the upturned portion 7^b preventing the same rolling off such tongue.

I claim:

1. A box or carton comprising a shell receiving vendible units; said shell having an opening at one end less in width than the body portion with a hollow space occupying a portion of said end of the box, and the upper wall of said space being slotted and the opposite wall of the box having a tongue adapted to enter said space through said slot.
2. A box or carton comprising a shell receiving vendible units; said shell having an opening at one end less in width than the body portion and the wall of such end being inturned to form a hollow space occupying a portion of said end of the box, and said upper wall being slotted and the opposite wall of the box having a tongue adapted to enter said space through said slot.
3. A box or carton comprising a shell receiving vendible units; said shell having an opening at one end less in width than the

body portion, with a hollow space occupying said end of the box, the upper wall of said space being slotted and the opposite wall of the box having a closure member with a tongue adapted to enter said space through said slot; said tongue serving as a shelf to receive a contained unit when the box is inverted after opening the same.

4. A box or carton comprising a shell receiving vendible units; said shell having an opening at one end less in width than the body portion and the wall of such end being inturned to form a hollow space occupying a portion of said end of the box and the upper wall of said space being slotted and the opposite wall of the box having a closure member with a tongue adapted to enter said space through said slot; said tongue serving as a shelf to receive a contained unit when the box is inverted after opening the same.

5. A structure such as set forth in claim 1, comprising front and rear walls and end walls; some of said walls having extensions for permanent engagement with other walls; one of said first-mentioned walls having an extended portion foldable into a hollow chamber disposed within the main shell.

6. A structure such as set forth in claim 1, comprising front and rear walls and end walls; some of said walls having extensions for permanent engagement with other walls; one of said first-mentioned walls having an extended portion foldable into a hollow chamber disposed within the main shell and including a top wall having a slot, and the vertical wall opposite said top wall terminating in a tongue adapted to pass into said chamber through said slot.

7. A structure such as set forth in claim 1, comprising front and rear walls and end walls having extensions for engagement with other walls; said front wall having an extended portion foldable into a hollow chamber disposed within the main shell.

8. A structure such as set forth in claim 1, comprising front and rear walls and end walls having extensions for engagement with other walls; said front wall having an extended portion foldable into a hollow chamber having a slot, and the rear wall having an extension including a tongue adapted to pass into said chamber through said slot.

9. A box or carbon comprising a body portion formed from a single section blank and made up of front and rear walls, end walls, a bottom wall and a closure section; one of said walls having an extension folded inwardly to form a space or chamber independent of the main chamber, and an integral tongue forming an extension of another wall and adapted to enter said supplemental chamber.

10. A box or carton comprising a body portion formed from a single blank and substantially rectangular in shape; one of the walls

thereof having an extension adapted to be folded inside the chamber of the main body and be secured thereto to form a space independent of the main space, and one portion of the wall extension forming such space being inclined and another portion thereof having a slot, and a cover section having a tongue adapted to pass through said slot and enter such supplemental space.

11. A box or carton comprising a body portion formed from a single blank and substantially rectangular in shape; the front wall thereof having an extension adapted to be folded inside the chamber of the main body and be secured thereto to form a space independent of the main space; and one portion of the wall extension portion forming such space being inclined and another portion thereof having a slot, and a cover section forming an integral extension of the rear wall and having a tongue adapted to pass through said slot and enter such supplemental space.

12. A box or carton having continuous side walls with an opening at one end, and a cover portion for said opening having a tongue for insertion in said end; said tongue having a plurality of folded portions to form sustaining means for articles discharged from said open end parallel with said folds when said cover portion is released.

13. A box or carton having continuous side walls with an opening at one end and a slotted wall partially covering said end, and a cover portion having a tongue adapted to enter said slot, said tongue having a plurality of folded portions to form sustaining means for articles discharged from said open end parallel with said folded portions when said cover portion is released.

In witness whereof I have signed this specification.

W. S. LUCKETT.
